CLAIM

The ornamental design for a combined dispenser and cap, as shown and described.

DESCRIPTION

FIG. 1 is a perspective view of the combined dispenser and cap, with the cap in place;

FIG. 2 is a front view showing the cap slightly displaced from the combined dispenser and cap;

FIG. 3 is a rear view showing the cap slightly displaced from the combined dispenser and cap;

FIG. 4 is a right side view of the cap slightly displaced from the combined dispenser and cap;

FIG. 5 is a left side view of the cap slightly displaced from the combined dispenser and cap;

FIG. 6 is a top plan view thereof; and,

FIG. 7 is a bottom plan view thereof.

FIG. 1 is on an enlarged scale.
